CALKED HORSESHOE

Norman C. Jeckel, P.O. Box ZZ,
Steamboat Springs, Colo. 80477

Filed Feb. 11, 1971, Ser. No. 114,747

Term of patent 14 years

Int. Cl. D30—99

U.S. Cl. D30—35

FIG. 3

FIG. 1.

FIG. 4

FIG. 2

FIG. 5

FIG. 1 is a top plan view of a calked horseshoe, showing my new design;

FIG. 2 is a bottom plan view;

FIG. 3 is a front elevational view;

FIG. 4 is a rear elevational view; and

FIG. 5 is a left side elevational view, the right side being substantially a mirror image thereof.

I claim:

The ornamental design for a calked horseshoe, as shown and described.
